UNITED STATES PATENT OFFICE.

ARCHIBALD E. MACQUARIE, OF MINNEAPOLIS, MINNESOTA.

EDUCATIONAL DEVICE.

Application filed August 11, 1924. Serial No. 731,238.

This invention relates to an educational device and its purpose is to provide an improvement in school room construction and equipment whereby the instruction of pupils 5 may be more conveniently and efficiently carried on. The instruction of pupils, particularly those in the lower grades, is attended with better results where maps, charts and cards carrying various instructional 10 data are displayed in combination with the blackboard, located in front of the class, so that the information contained on the charts, maps and the like may be supplemented by other instructional data placed 15 alongside on the blackboard by the instructor, or the pupils may be caused to copy on the blackboard, adjacent the displayed chart or card, the lesson which is so displayed, or other instructional material, such as examination 20 questions, displayed on the blackboard may be temporarily covered by charts, sheets or the like which are mounted in position adjacent the blackboard and removed during the process of instructing or examining 25 the class. There are various situations in which the display of charts, maps, cards and the like on the wall of the room are desirable, preferably in combination with the blackboard, and the advantage of 30 such display is often increased by the ability to shift the cards, charts and the like longitudinally of the wall so that they may be displayed successively or moved from one position to another for the instruction of 35 different sections of a class. It is the principal object of the present invention to provide an improved school room construction whereby maps, charts, cards and the like may be displayed on the wall of the school 40 room. Another important object is to provide an improved school room construction whereby maps, charts, cards and other instructional devices may be displayed in combination with the blackboard. Other objects and advantages of the invention will 45 appear more clearly hereinafter.

The nature of the invention will be understood from the following specification taken with the accompanying drawings in 50 which one embodiment is illustrated. In the drawings Figure 1 shows a perspective view of a portion of a school room showing the embodiment therein of the features of the present invention; Fig. 2 shows a sectional view taken on the line 2—2 of Fig. 55 1 looking in the direction of the arrows,

and Fig. 3 is a perspective view of a portion of the display device by which maps, charts, cards and the like are mounted in position on the wall of the room.

The present invention comprises a school room having a wall 10, located in front of the class, side walls 11, a floor 12, and a ceiling 13. On the wall 10 located in front of the class there is mounted a blackboard 14 having along the bottom thereof a rail or shelf 15 adapted to support erasers and the like in the usual manner and having along the top edge thereof the usual molding 16. There is mounted above the blackboard, preferably in proximity to the top edge thereof, a longitudinal slotted bar 18 having the form illustrated more particularly in Fig. 3, this bar comprising a rear wall 19, a top wall 20, a bottom wall 21, a flange 22 extending downwardly from the front edge of the top wall 20, and a flange 23 extending upwardly from the front edge of the bottom wall 21, all these parts being formed as an integral construction, preferably by rolling them from sheet-metal. The rear wall 19 is provided with a plurality of apertures 24 adapted to be engaged by screws 25 for securing the bar to the wall. The top wall 20 is provided with a rectangular opening 27 which preferably has a notch 28 extending downwardly therefrom through the flange 22 and forming a communication between the opening 27 and the longitudinal slot 29 which extends longitudinally of the bar between the edges of the top flange 22 and the lower flange 23.

The openings 27 and communicating notches 28, which may be distributed as intervals throughout the length of the bar 18 95 across the width of the school room, are adapted to permit the insertion into and withdrawal from the under-cut groove of the slotted bar 18 of a plurality of holding blocks or plates 30 and 31. The blocks 30 100 are rectangular in form and formed preferably of material such as rubber, cork, linoleum, wood, or the like, which may be perforated by thumbtacks 32 or other sharp devices adapted to engage the maps or other sheets to be supported. The corners of the blocks 30 are rounded as shown at 33 so that the edges will not catch on the corners of the openings 27 and 28 when the blocks 30 are caused to move longitudinally in the 105 under-cut groove of the supporting bar. The other supporting members 31 are similar in 110

shape to the blocks 30, having rounded corners 34, but they may be formed of metal or other similar material and are provided on their front sides with supporting hooks 35 which are adapted to project outwardly through the slot 29 of the bar to engage eyelets or other supporting devices carried by the maps or charts to be displayed. When the holding members 31 are inserted into or withdrawn from the slotted bar, the hooks 35 are adapted to pass through the notches 28, these notches being unnecessary to permit the insertion and withdrawal of the holding blocks 30 which are employed in connection with the thumb-tacks 32. The longitudinal dimension of the notches 28 should preferably be less than the longitudinal dimension of the holding blocks 30 and 31 so that when these blocks are caused to slide longitudinally of the bar 18 past any one of the openings 27, the portions of the flange 22 at each side of each notch 28 will prevent the holding blocks 30 and 31 from tilting outwardly.

25 Although there are various devices bearing instructional data which may be displayed on the wall of the school room according to the present invention, there are illustrated in Fig. 1 certain articles which 30 are displayed over the surface of the blackboard by means of the display device herein described. The card or sheet 40 may be a card bearing an example of penmanship which is displayed to the class and which 35 may be preferably copied by them in the space on the blackboard immediately beneath the card or sheet. The sheet 41 may be a chart displaying the spelling lesson of the class and this spelling lesson may be 40 studied from the chart or copied by the pupils on the blackboard and may be readily replaced by another lesson or chart simply by removing the thumb-tacks 32 by which the chart is attached to the holding blocks 45 30 mounted in the slotted bar 18 above the blackboard. The numeral 42 is used to designate a cover sheet having holding straps 43 which are suspended from hooks 35 on the holding blocks 30 mounted in the slotted bar 50 18 so that the cover sheet may be employed to cover up examination questions, for example, which are designated by the numerals indicated at 44, so that after the class is assembled and in readiness to receive the 55 examination, the cover sheet may be removed, preferably by sliding the blocks 34 longitudinally of the bar 18 in the under-cut groove thereof. At the right of the blackboard, as illustrated in Fig. 1, there is shown 60 a picture 45 having suspended members 46 which are attached to hooks 35 carried by the supporting blocks 31 which are movable in the slotted bar 18. This picture may be copied on the blackboard by one or more 65 pupils or it may be used for the instruction

of the class and then shifted longitudinally to a new position, for the instruction of another section of the class, for example. There are various other ways in which the maps, charts, and other instructional devices 70 may be displayed on the wall of the school room according to the present invention and there are many advantageous uses for the practice of shifting the cards or other devices displayed from one position to another 75 during the progress of the class instruction. The foregoing explanation will be sufficient to indicate the advantage and merit of the present invention according to which the various instructional charts, maps, cards and 80 the like are displayed on the wall of the school room preferably in combination with the blackboard, and in such manner that they may be shifted over the wall of the room from one position to another without 85 detaching them from their supports.

Although a certain construction and certain practical uses of the present invention have been illustrated by way of example, it will be understood that the invention may be 90 constructed and practiced in various ways without departing from the scope of the appended claims.

I claim:

1. The combination with a blackboard, of 95 supporting means holding said blackboard in fixed position, a display device carried by said supporting means over said blackboard, holding means slidably longitudinally of said display device, and educational and instructional devices detachably carried by said holding means and movable over the surface of the blackboard to cover any part thereof and leave any part of said blackboard exposed, as desired. 100

2. The combination with a blackboard, of a slotted bar extending longitudinally of and above said blackboard, a holding member slidably mounted in said slotted bar for movement longitudinally thereof, 110 said bar having openings to permit the insertion of said holding member at various points between the ends of said bar, supporting means projecting from said holding member through the slot of said bar, and a 115 chart detachably supported on said supporting means and suspended therefrom in front of said blackboard.

3. The combination with a blackboard of a longitudinal bar extending above said 120 blackboard and having a slot in the front side thereof, a holding member slidably longitudinally in said bar, said bar overlapping the upper and lower edges of said supporting member, said bar having openings in the side thereof to permit the insertion of said holding member into said bar at points between the ends thereof, supporting means carried by said holding member and projecting through the slot of said bar, 125 130

and a chart detachably mounted on said supporting means and movably located in front of said blackboard.

4. The combination in an educational device of a blackboard, a longitudinally slotted bar mounted above said blackboard, a plurality of holding members slideable longitudinally in said slotted bar, said bar having openings in the side of its slot to permit the insertion of said holding members at points between the ends of said bar, and means carried by the said holding members for supporting instructional devices in proximity to the face of said blackboard, said openings permitting said instructional devices to be super-imposed and to be arranged between each other longitudinally of the blackboard as desired without interfering with other educational or instructional devices so supported.
5. The combination in an educational device of a blackboard, a bar supported horizontally above said blackboard, said bar having an under-cut slot therein provided with said openings at intervals along the length of the bar, a plurality of holding devices each insertable into said under-cut slot through one of said openings, and a plurality of educational charts carried by said holding devices and suspended therefrom in front of said blackboard.
6. The combination in an educational device of a blackboard, a slotted bar extending longitudinally of and above said blackboard, relatively movable holding members slideable longitudinally in said slotted bar, said bar having upper and lower flanges for retaining said holding members in said bar, one of said flanges having openings to permit the insertion and withdrawal of said holding members at points between the ends

of the bar, instructional devices, and means carried by said holding bar for supporting said instructional devices in proximity to the blackboard, said holding members and openings permitting said instructional devices to be arranged between each other longitudinally of the blackboard without interfering with other instructional devices so supported.

7. The combination in an educational device of a blackboard, a slotted bar mounted in proximity to said blackboard and extending longitudinally thereof, relatively movable holding members slideable longitudinally in said slotted bar, said holding members being formed of relatively soft material capable of being readily perforated by thumbtacks, instructional devices, and thumbtacks engaging said instructional devices and said holding members for supporting said instructional devices over the face of said blackboard.

8. The combination in an educational device of a blackboard, a slotted bar mounted in proximity to said blackboard and extending longitudinally thereof, relatively movable holding members slideable longitudinally in said slotted bar, said holding members being formed of relatively soft material capable of being readily perforated by thumbtacks, the wall of said bar at one side of said slot being provided with a plurality of openings to permit the insertion and withdrawal of said holding members at points between the ends of said bar, instructional devices, and thumbtacks engaging said instructional devices and said holding members for supporting said instructional devices in various positions over the face of the blackboard.

ARCHIBALD E. MACQUARRIE.
